(57) **CLAIM**

The ornamental design for deck box, as shown and described.

DESCRIPTION

FIG. 1 is a perspective view of a deck box showing my new design; and,

FIG. 2 is a front elevational view, the rear elevational view being a mirror image thereof.

Phantom lining, where utilized, is for illustrative purposes only, and is not intended to limit the claimed component design to the features shown in phantom.

1 Claim, 2 Drawing Sheets

FIG. 2
